UNITED STATES PATENT OFFICE.

DOROTHY READ, OF FORT SMITH, ARKANSAS.

DESIGN FOR A DOLL.

59,282.

Specification for Design.

Patented Oct. 4, 1921.

Application filed May 23, 1921. Serial No. 471,991. Term of patent 14 years.

To all whom it may concern:

Be it known that I, DOROTHY READ, a citizen of the United States of America, residing at Fort Smith, in the county of Sebastian and State of Arkansas, have invented a new, original, and ornamental Design for Dolls, of which the following is a specification, reference being had to the accompanying drawing, forming part thereof.

Fig. 2, is a rear view of the same.

I claim:

The ornamental design for a doll, as shown.

DOROTHY READ.

Witnesses:

HENRY C. READ,
S. M. NANCE.
